UNITED STATES PATENT OFFICE

ALEXANDER MARTINEK, OF WORCESTER, MASSACHUSETTS, ASSIGNOR TO PRAGER CO., INC., A CORPORATION OF NEW YORK

DESIGN FOR WALL PAPER OR SIMILAR MATERIAL

Application filed March 17, 1930. Serial No. 34,916. Term of patent 3½ years.

To all whom it may concern:

Be it known that I, ALEXANDER MARTINEK, a citizen of the United States, and resident of Worcester, in the county of Worcester and State of Massachusetts, have invented a new, original, and ornamental Design for Wall Paper, or Similar Material, of which the following is a specification.

In the accompanying drawing:

The figure is a surface view of a piece of wall paper or similar material showing the design. The area within the dot and dash lines shows one complete unit of the

design. The repeats are arranged in vertical rows, and adjacent vertical rows are one half a complete unit offset so that the angle of the complete unit designated by the letter A corresponds with the angle B of a repeat in an adjacent vertical row.

I claim:

The ornamental design for wall paper or similar material as shown and described.

Signed at New York in the county of New York and State of New York this 1st day of March A. D. 1930.

ALEXANDER MARTINEK.
